UNITED STATES PATENT OFFICE.

WILLIAM D. PIERSON, OF WATERBURY, CONNECTICUT, ASSIGNOR TO THE WATERBURY FARREL FOUNDRY & MACHINE COMPANY, A CORPORATION OF CONNECTICUT.

WIRE-DRAWING MACHINE.

1,354,336.

Specification of Letters Patent. Patented Sept. 28, 1920.

Application filed March 13, 1919. Serial No. 282,399.

To all whom it may concern:

Be it known that I, WILLIAM D. PIERSON, a citizen of the United States of America, and a resident of Waterbury, county of New

5 Haven, and State of Connecticut, have invented certain new and useful Improvements in Wire-Drawing Machines, the principles of which are set forth in the following description and accompanying drawings,
10 wherein is disclosed the form of the invention which I now consider to be the best of the various forms in which said principles of the invention may be embodied.

This invention relates to improvements in
15 wire-drawing machines or benches and involves improvements particularly upon the wire-drawing machine of United States Patent No. 1,025,421 of May 7, 1912. The invention comprises block-braking apparatus coöoperating with the apparatus of the machine of the above patent for automatically releasing the clutch from the wire-drawing block, and in minor features of construction of said apparatus including the
25 25
brake itself. The invention hereof may be used in various modifications of wire-drawing machines other than that of said prior patent.

Of the drawings, which show the machine
30 of said prior patent with the invention hereof embodied therein, Figure 1 is a plan and Fig. 2 a front elevation of the relevant parts of the machine showing the rotatable wire-drawing block or wire-winding drum 11 with inclosing top cover 48 and bottom flange 101; also the table 1 on which are mounted said block 11 and the die-holder 55X; said table 1 being supported by legs 2 (Fig. 5).

40 Fig. 3 is a plan view showing certain novel details of the apparatus for tripping or releasing the power clutch mechanism inclosed in block 11 of Figs. 1 and 2, through action of treadle bar 34X, which in turn operates the brake motion on the wire drawing block, see Figs. 5 to 10. (A front elevation of said tripping apparatus of Fig. 3 is shown in Fig. 2).

Fig. 4 is a side elevation of part of the
45 tripping mechanism of Figs. 2 and 3, said

part illustrating also the operation of the controlling treadle 34X by the tripping mechanism, this treadle being the same controlling part by which the internal coil clutch and the brake are applied alternately 55 to block 11 as shown in Fig. 5.

Fig. 5 is a transverse vertical section through the entire machine (save block 11 wherein the clutch mechanism is shown in dotted lines) showing the operating treadle 60 or control lever 34X (which is also shown in Fig. 7 and partially in Fig. 2), and showing also the connections whereby said treadle operates the coil-clutch 15 inclosed in block 11, and the connections whereby said treadle 65 operates the brake 100 shown in transverse vertical section at the upper right of the figure.

Fig. 6 is a rear elevation of the mechanism of Fig. 5 showing the details of the 70 brake of Fig. 5 in section at the upper part.

Fig. 7 is a plan partly in section of the treadle or control lever 34X of Figs. 2 and 5, together with the supports for this treadle and for the parts operated by it. 75

Fig. 8 is a plan of the brake with cover removed to show the inside braking mechanism shown also in Figs. 5 and 6.

Fig. 9 is a horizontal section of the arrangement of pin 86 of Fig. 5; and 80

Fig. 10 is a horizontal section of the arrangement of pin 75 of Fig. 5.

Figs. 11 and 12 illustrate a modified construction of the brake having an operation similar to the construction shown in the 85 Figs. 5, 6 and 8, this construction being preferable in some cases.

The driving means (shown in Fig. 5 center from top to bottom) for the wire-drawing block 11 may be and is indicated as the same 90 as in said prior patent. It is described briefly hereinafter. In this invention the control lever or treadle bar 34X (Figs. 5, 2 and 7) is the mid-point of the system of control connections for power and brake. The 95 two ends of said system controlled by treadle 34X are (1) the brake 100 (Fig. 5 upper right) and (2) the die holder 55X of Figs. 1 and 2 starting with the treadle 34X as the mid-point between the two as shown at the 100

left in Fig. 5 and at the lower right of Fig. 2. This control system extends up through the automatic tripping mechanism of Fig. 2 to the die-holder 55X thereof which operates with the wire and grip (not shown here) in block 11 to draw the wire through the die (Fig. 2 center top), the wire being pulled to the right and coiled around block 11 in its anti-clockwise rotation indicated by arrow. (The wire-grip is shown at 51 in said prior patent). The connections by which the tripping mechanism of Fig. 2 operates to automatically disconnect the power from and apply the brake to the block 11 are shown in Fig. 5 and include treadle bar 34X and parts above it.

The object of the invention is to provide a practical tripping and braking combination whereby the release of the drawing strain on die-holder 55X will result automatically in a disconnection of the driving means from the rotatable drawing-block or drum 11 and will result in the braking of said block; and also to provide a construction permitting the brake to be released by the operator either with or without applying the power to rotate said block 11.

The block or drum 11 is shown in Figs. 1, 2 and 5, and the die-holder 55X in Figs. 1 and 2. The drawing strain on die-holder 55X is released either when the last of the wire has been drawn through the die or when the wire itself breaks in two. The block 11 (with the parts inside and moving with it) is quite heavy and in its operating rotation has considerable moment of inertia so that when it is cut off from the driving mechanism of Fig. 5 by the tripping mechanism of Fig. 2, it rotates freely unless braked, carrying with it the wire-grip which flies out from the block and also the projecting length of wire which thrashes around during the continued rotation of the block and is liable to result in injury to the operator or cause serious entanglement. The brake hereof and its connections for automatic and manual operation are designed to apply the brake immediately (Fig. 5) to flange 101 of rotating block 11 in order to prevent the above evils and they also constitute further improvements.

For simplicity the reference number system used herein is as follows. Numbers up to and including 73 indicate that the parts to which they are applied correspond generally in function with the parts of said prior patent which are numbered likewise; and of such numbers those followed by an X indicate a modification of structure; and those numbers which are not followed by an X indicate both structure and function as before. Certain numbers up to 73 are omitted thereby indicating that parts in the prior patent so numbered are not here used.

Numbers higher than 73 indicate parts herein which are additional to anything shown in the prior patent.

First consider the tripping connections on Figs. 1 and 2, whereby the movement of the die-holder operates treadle 34X to disengage the power and apply the brake. In Fig. 1 (on line O—116—O) and Fig. 2 (on line O—57—O), die holder 55X is shown in full lines in its drawing or operating position, *i. e.* with the wire tangent to the block Fig. 1, and (Fig. 2) against the shoulder of block-flange 101. The approximate starting position of said die-holder 55X is (Fig. 1) along line S—116—S, and (Fig. 2) along line S—57—S. The die-holder 55X has both horizontal movement (Fig. 1) and vertical movement (Fig. 2). It is held in its operating positions (O—116—O, Fig. 1 and O—57—O, Fig. 2) by the drawing tension of the wire which is pulled through the die by the rotation of block 11. When the last or a broken end of the wire has been pulled through the die toward the right, to block 11, so that the drawing tension of die-holder 55X is removed, the weight 107, suitably located on horizontal lever 106 to overbalance the weight of die-holder 55X with its die, etc., pulls down slide 110 (Fig. 2), horizontal lever 106 moving from its operating position 104—O to starting position 104—S. The location of starting position 104—S is established by adjustment of screw 59 (Fig. 2) in lug 60 on die-holder 55X, that is, the upward motion of the die-holder is stopped when this screw hits against the upper lug of bracket 58X. This limiting upper position corresponds to line S—57—S in Fig. 2.

At 105 (Fig. 2) the horizontal rod 106 is received by a socket in the end of bell-crank lever 102 pivoted at 104 to supporting plate 37X of the machine. (This plate is shown in edge view in Figs. 4 and 5 and in horizontal section in Fig. 7). Weight 107 depresses rod 106 operating on its pivot 104. In Fig. 2 bell crank lever 102 is shown in the position corresponding with the drawing or operating position of the other movable parts in the figure, its lower end being connected by pin 103 with a rocking lever 69X pivoted in plate 37X at 68X. The lower end of lever 69X is provided with a screw 70 held in readiness to push treadle 34X to the left by the automatic tripping operation so that said treadle is pushed out of engagement under horizontal shoulder 40 of vertical slot 39. In the drawing operation of the machine the treadle 34X is held under said shoulder 40 by a spring pulling upwardly (41 in Fig. 5). In Fig. 2 the depression of horizontal rod 106 to the starting position S—104 moves bell crank lever 102 on its pivot 104 so that its lower end moves to the right. This rocks lever 69X on its pivot 130

68X so that its lower end moves to the left and screw 70 engages treadle 34X and the latter is forced to the left into vertical slot 39 up which it is pulled by spring 41 into 5 its upper position 34X of Fig. 2, which position corresponds with the starting positions "S" of the parts above specified. This upward movement of treadle 34X results in the disconnection of the driving 10 means shown in Fig. 5 from block 11, and also results in the braking of said block as the result of the consequent operation of the connections from treadle 34X shown in Fig. 5 and now to be described.

15 In Fig. 5 is shown treadle 34X having a vertical motion in slot 39 (Figs. 2 and 5) in supporting plate 37X, this being the plate on which in Fig. 2 bell crank lever 102 and rocking lever 69X are pivoted. In Fig. 5 20 treadle 34X is pivoted at its extreme right end at 84 to a leg or support 2 of the machine. Treadle 34X has two sets of operating connections, one to the driving means for block 11 inside the same (dotted lines) 25 and the other to brake 100 which is applied to the periphery of flange on base 101 of block 11. Treadle 34X in its lowermost position causes the continuous application of the driving power to rotate block 11. This 30 is the position of the treadle indicated at O—84, which corresponds to the drawing or operating positions of the parts shown in Figs. 1 and 2 and there also indicated by the lines lettered "O". In Fig. 5 the connections from treadle 34X to the coil clutch driving apparatus are the turn-buckle 36X having its lower end connected to treadle lever 34X and its upper end connected to 35 the fork lever 32X, the latter and all the rest of the power apparatus being, if desired, of the same form as in said prior patent and operating to rotate drawing-block 11 by means of coil clutch 15 inside said block, the power being applied from main 40 shaft 5, gear 9 thereon and gear 8 on vertical shaft 7. When treadle 34X is in its lowermost position O—84 (when it is held under shoulder 40) drawing block 11 is being rotated by coil clutch 15 which is held 45 in its clutching position by the connections from treadle 34X, which include turn-buckle 36X lever 32X etc. As in said prior patent the fork-lever 32X is hinged at 33 to a leg or support 2 of the machine, and 50 it operates the coil clutch 15 in block 11 by the mechanism shown in detail in said prior patent and shown here generally in dotted lines in Fig. 5 as follows: Lever 32X is forked to receive pins 31, which project 55 from a part rotatably connected with hub 27 secured by pintle 28 to vertical rod 23 which reciprocates in the hollow interior of power shaft 7. Rod 23 extends up through the top of continuously rotating shaft 7 and at upper end of said shaft is a plate 24 secured 60 to the upper end of rod 23 and mounted to rotate with shaft 7. When rod 23 is pulled down inside shaft 7 by the depression of treadle 34X to its position O—84, said rod 23 depresses plate 24 sliding on shaft 7 to 65 engage a lever 19 and thereby cause coil 15 to clutch hub 14 which is fixed to shaft 7 coil 15 being fixed to block 11 so that now shaft 7 is clutched via coil 15 to block 11 and causes the rotation of the latter. The 70 clutch-operating position of fork lever 32X is indicated in Fig. 5 by the line O—33. The positions of the parts shown in Fig. 5 are those corresponding to the non-wire-drawing condition of the machine which is 75 at rest save for the driving mechanism as far as and including shaft 7. For example, fork-lever 32X is shown in its position ready to start operation of the machine, this position being indicated at S—33. But its 80 position which corresponds with the positions of the parts shown in Figs. 1 and 2 is at O—33 Fig. 5, and the corresponding position of the treadle 34X is its lowest indicated at O—84 in Fig. 5.

85 As soon as treadle 34X has been forced to the left (Fig. 2) from its lowest position in vertical slot 39 under shoulder 40 its spring 41 (Fig. 5) pulls it up through slot 39. At this time fork-lever 32X is pulled 90 up to the position shown in Fig. 5 by means of its spring 78, which is secured at 80 to a downward projection added to lever 32X for the purpose of receiving said spring 78 at the proper point. Connection 36X between treadle 34X and fork lever 32X is in 95 the form of a turn-buckle, in order to permit of adjustment. These modifications and also the middle bend in treadle lever 34X for the purpose of clearing the main 100 shaft 5 and its bearings are all made in relation to the braking apparatus.

105 For clearness, brake 100 is not shown in Figs. 1 and 2 which show the drawing operation positions of die-holder 55X and its 110 associated parts when the brake is not applied. Similarly in Fig. 5 the wire-drawing parts (die-holder 55X etc.) are omitted for clearness because they are not in operation when the brake is applied as shown in this 115 Fig. 5. That the brake is applied in Fig. 5 is indicated by the fact that treadle 34X is in its uppermost position indicated by line A—84, the power being disconnected from block 11 when treadle 34X is in its 120 uppermost position.

125 In Fig. 5 coil-clutch 15 is shown as released but ready to be applied to rotate block 11 by a depression of treadle 34X; block 11 being held meanwhile against rotation by the spring action of the brake, the details of which are shown in Figs. 6 and 8, in addition to Fig. 5, a modified construction being shown in Figs. 11 and 12. In Fig. 5 are shown the brake applying positions 130

along lines lettered "A" of the connection between treadle bar 34X and the brake as follows: At the right, at 82 in treadle lever 34X is pivoted the lower end of a turn-buckle 83, the upper end of which is pivoted at 81 to a lever 85 the other or left end of which is keyed fast to a stud or pin 86, which is mounted to oscillate in leg or support 2 of the machine (for details see Fig. 9). To said oscillating stud 86 is keyed fast a lever 87, which extends upwardly through table 1 to the braking mechanism mounted on top of table 1, and shown in section. The above parts in the position shown permit a spring application of the brake toward the left against bottom flange 101 of block 11 these positions of the operating levers being indicated by the line A—86—A. The line O—86—O indicates the positions of the above connections for the extreme withdrawn position of the brake which positions correspond with the lower-most treadle position O—84—O corresponding to the drawing operation of the machine as shown in Figs. 1 and 2, when the die-holder 55X (Figs. 1 and 2) is in its drawing position wherein the end of the system operated by the die-holder 55X (see screw 70, Fig. 2, lower right hand) remains at the right to permit treadle 34X to remain beneath shoulder 40 and hold the brake in its released position.

The intermediate position of treadle 34X and of the brake connections in Fig. 5, all lettered B, will now be described. The reason for these intermediate positions is the desirability of permitting the operator in preparing to start the machine, to release the brake before connecting block 11 with the power mechanism which rotates it. If the brake be released while the first end of the wire is being secured in the grip of block 11, the operator can manually turn block 11 and swing it around to the position most convenient for him to fasten the wire in the grip in block 11. During this time die-holder 55X and its connections remain in their upper positions along the lines lettered S in Fig. 2, screw 70 (Fig. 2 lower right hand) being then located to the left of its position shown, *i. e.*, extending into the space shown as occupied by the lower position of treadle 34X. In order to change treadle 34X from its intermediate position B—84 (Fig. 5) the operator depresses it until latch 119, pressed toward the right by the operator's toe, is engaged by its lug 120 in a small supplementary slot 123 (Figs. 5 and 2) at the top of vertical slot 39 in support plate 37X. Spring 41 now holds the parts in this position; the operator can draw his foot from the tread 124 of treadle bar 34X and attend to securing the wire end in the grip of block 11. During said part-way depression of treadle 34X the driving

means has not yet been connected to block 11 to rotate it, for the reason that the turn-buckle connection 36X has a loose connection with treadle bar 34X consisting of a pin 75 in the treadle bar which plays in a slot 76 in turn-buckle 36X (for details see Fig. 10), a set screw 118 adjusting the extent of looseness of this connection. Hence, with both power and brake disconnected, the operator can move block 11 freely while gripping the first end of the wire to it.

After the operator has completed the gripping of the wire to block 11, he may start the machine by further depression of treadle 34X from its intermediate position B—84, Fig. 5, down to its lowest position O—84, which corresponds with the "O" positions of all the parts so marked in Figs. 1, 2, and 5. The small top slot 123 for lug 120 of latch 119 is curved on its lower side (Figs. 5 and 2) so that as treadle 34X goes down, the lug 120 goes down with it; and as lug 120 moves down, it also moves to the left under action of spring 122, the whole latch 119 swinging to the left on its pivot 121 and against the tread 124 of treadle bar 34X. (On this occasion of the operation of treadle 34X, the operator's toe is, of course, not pressed against latch 119.)

As treadle 34X now goes down toward its lowest position O—84 its pin 75 engages the screw 118 in the lower end of the slot 76 in turn-buckle 36X and by the operation of the latter the driving mechanism is clutched to operate block 11 as described above, whereupon the wire to be drawn is put under tension die-holder 55X is moved into its drawing position O (Figs. 1 and 2) and the various connections of Fig. 2 described are operated by said movement of the die-holder with the result that screw 70 (Fig. 2 lower right) moves to the right into the position in which it is shown, being moved out from under shoulder 40 so that treadle 34X is free to be shoved by the operator sidewise from vertical slot 39 to the right to engage under shoulder 40. At this point the machine is left to its operation until such time as the drawing of the wire is completed, or until the wire breaks, whereupon the above described cycle of operations is repeated, beginning with the automatic disconnection of the driving power and the automatic application of the brake, and continuing with the operator's release of the brake and application of the power by the two successive part-way depressions of treadle lever 34X. In the two positions of the brake connections indicated in Fig. 5, upper right, *i. e.*, B—86—B and O—86—O the brake is equally and fully released. The only significance in said indications of these two positions is that the B position corresponds to the intermediate or B position of treadle 34X *i. e.*, its position before the power is ap-

plied to block 11, this being the period of time when the operator is gripping the wire to block 11.

5 *Construction of die-holder, etc.*

These are the features shown in Figs. 1-4.

As shown in Fig. 2 the drawing-die marked "Die" is held against arms 54 of die-holder 55X by a screw operated by wheel 127. It is through this die that the operator threads the pointed end of the wire which is then passed on to the grip in block 11. During the period when treadle 34X is 10 in its intermediate position B—84, Fig. 5, the die-holder 55X is in starting position S—116—S, Figs. 1 and 2, that is, after the wire has been gripped in block 11. When 15 treadle 34X thereafter is depressed to its 20 lowest point O—84 Fig. 5, then block 11 pulls the wire taut which pulls die-holder 55X around (Fig. 1) until it occupies the drawing or operating position O—116—O tangent to rotating block 11. To permit 25 this movement die-holder 55X is secured to swivel block 56 (Fig. 2) centered on vertical pin 116 (Figs. 1 and 2) in bracket 58X adjustably secured to table 1 of the 30 machine. The securing of die-holder 55X to swivel block 56 is by means of horizontal pivot 57 in block 56 whereby when the wire under tension swings the die-holder around on vertical pivot 116 (Fig. 1) it also pulls 35 it down around pivot 57 (Fig. 2) into its drawing position O—57—O in Fig. 2. Hence die-holder 55X has the ability to move in two directions which is utilized in starting the machine as shown in Figs. 1 and 2.

40 The following is the construction (Figs. 1 and 2) whereby the ability of die-holder 55X to move vertically controls the disconnection of power from block 11 and the application of the brake thereto by 45 means of the connections in Figs. 2 and 5 hereinbefore described. The fixed bracket 58X (Fig. 2) is H-shaped, having top and bottom pairs of lugs 113 extending to the left. The vertical space between said lugs 50 is occupied by vertical slide 110 which projects down through hole 117 in table 1 of the machine. A pin 111 extends through the portion of slide 110 which lies between the upper and lower pairs of lugs 113 on 55 fixed bracket 58X. The ends of said pin 111 are mounted in the ends of two arms 115 of die-holder 55X. Said arms 115 are spaced apart (Fig. 1) so as to straddle fixed bracket 58X, and this construction 60 permits the operator when threading the end of the wire through the die to manually swing the die-holder freely toward him (without interference from fixed bracket 58X) and beyond the die-holder's 65 drawing position O—116—O of Fig. 1 and

approximately to the front of table 1 into a position most convenient for the operator. Then after having threaded the wire through the die, the operator may swing back the die-holder to permit him to grip 70 block 11 the end of the wire projecting through the die to the right. The vertical slide 110 (Fig. 2) is held in place between the pairs of lugs 113 by vertical cover 114. Pin 111 in the ends of die-holder 75 arms 115 moves up and down in the vertical space between the upper and lower pairs of bracket lugs 113. The horizontal slot 112 in vertical slide 110 which receives pin 111 allows for the slight horizontal movement of said pin when die-holder 55X swings vertically on its horizontal pivot 57 (Fig. 2). The lower end of slide 110 carries a pin 109 engaging in a slot in horizontal rod 106, this permitting an adjustment 80 of fixed bracket 58X to right or left along table 1 in order to place the die end of the die-holder 55X the desired distance from the grip in block 11. Horizontal rod 106 carries a weight 107 adjustable along its 85 length and held thereto by set screw 108. In the normal or drawing operation of the machine, weight 107 is held up in the position shown, by the wire being drawn, which acts through the parts above described, but 90 as soon as the drawing of the wire has been completed, or in case the wire breaks, then weight 107 counter-balancing die-holder 95 55X drops down and causes the parts to assume their starting positions "S" (Figs. 1 and 2) by way of the pulling down of slide 110 and pin 111 and the vertical swinging of die-holder 55X on its horizontal pivot 57. This operation moves the parts at the 100 lower right in Fig. 2, as above described, so that the screw 70 pushes treadle 34X to the left out of engagement under shoulder 40 with the result that the power is disconnected from and the brake applied to the 105 rotating block 11. Some operators prefer shoulder 40 (Fig. 2) on the opposite or left hand side of a vertical slot 39 in plate 37X. For such cases a re-arrangement of the levers can be 110 easily made which will produce a motion of screw 70 to the right instead of the left, in order to kick out the treadle bar 34X from shoulder 40. In such arrangement latch 119 (Figs. 2 and 5) and supplementary shoulder 123 will be located on the opposite 115 side, together with such other minor details as are required for this arrangement. Otherwise the same motion of die-holder 55X weight 107 on bar 106, and the brake 120 details are maintained as before, being produced by pressing down the foot treadle 124 on bar 34X, to start the block 11 in rotation and also release the brake 100. Conversely when the wire breaks or pulls 125 through the die, the upward swing of the 130

die-holder 55X kicks out the treadle bar 34X and applies the brake 100.

It has been stated above that the clutch 15 inside die-holder 11 is released and the 5 brake 100 applied when the last end of the wire pulls through the die, or if the wire should break in drawing, this being brought about by the upward swing of the die-holder 55X. The following also is a fact. 10 In the event of any emergency while the block 11 is in rotation drawing wire through the die, the operator may at any time kick out the treadle bar 34X from shoulder 40, which will immediately release the clutch 15 and apply brake 100 independently of 15 any motions on the part of the die-holder 55X, with its connections for the automatic trip. This will be evident from the drawings.

20 *Brake construction.*

The first form is shown in Figs. 5, 6, and 25 8. The brake shoe is a slide 93 having lateral extensions to provide ample bearing surface and conforming to the periphery of flange 101 of block 11 against which shoe 93 is pressed by helical spring 95 in holes 25 96 in shoe 93. A leather facing 100 is preferably interposed on the face of shoe 93. The brake is shown in Fig. 5 as applied to the rear side of block 11, this being a convenient location both for the brake itself and for the operating connections from treadle bar 34X.

30 35 In Figs. 5 and 8 the brake is shown in action applied to block 11 under compression of springs 95 which springs are permitted to act by the operating connections to treadle 34X that is, by movement of lever 87 to the 40 left on its pivot 86 (Fig. 5).

The center of shoe 93 has a machined recess 126 (Fig. 8) to receive the upper end of lever 87, and to receive also the screw adjustment for the purposes of regulating the 45 pressure of lever 87 and of taking up wear. Shoe 93 is contained within a bracket or housing 97 secured by screws 98 to table 1 of the machine. The housing is provided with a top cover 99, which is removed in 50 Fig. 8 to show a plan of the parts inside. Housing 97 is open toward block 11, and also at its bottom so that shoe 93 slides directly on the finished surface of table 1 of the machine. The rear ends of springs 95 abut 55 against the rear wall 125 of housing 97. The screw adjustment is as follows. Adjusting screw 92 extends out through housing rear wall 125 (Fig. 5) for ready access. Screw 92 has a shoulder which engages adjustment-block 94 which fits and is adjustable in finished shoe-recess 126 (Fig. 8). Adjusting block 94 is engaged by the top 88 of lever 87 in its movement to the right for the purpose of overcoming the compression

of springs 95 and releasing the brake. The 65 screw 92 extends loosely through a recess 89 (Fig. 6) in lever-top 88, but its threads engage in a lock-nut 128 and in shoe 93. There is a slight clearance opening as shown (Fig. 5) between lock-nut 128 and lever top 88, and it is the springs 95 and not lever top 88 which press shoe 93 to the left to its braking position. When lever-top 88 is moved to the left (Fig. 5) the compression springs 95 are freed to press shoe 93 and its facing 100 70 against block flange 101, and the springs always, via shoe 93 and screw 92, pull adjustment block 94. The only operating motion required for the brake shoe 93 upon the finished surface of table 1 is a short travel 75 to and from block-flange 101, and that is effected at the times and by the operating connections hereinbefore described.

In the modified construction of brake and its immediate operating connections shown 85 in Figs. 11 and 12, the braking compression of springs 95 is countered and the brake thereby released by means of the wedge action of a plunger 87A rising vertically against adjustment block 94A which acts 90 against the shoulder of adjusting screw 92 as before. In this instance parts 87A and 94A are constructed to permit the wedge action, as shown. Plunger 87A is pivoted to one end of oscillating lever 85A mounted at 95 86A to a leg or support 2 of the machine (Fig. 5), the other end of the lever 85A being pivotally connected at 81A to the upper end of turn-buckle 83 of Fig. 5. When plunger 87A is pulled down, compression springs 95 are free to force brake shoe 93 against block flange 101 as before, and the construction and operation in all other respects is the same as in Figs. 5, 6, and 8.

100 I claim—

1. In a wire-drawing machine, the combination with the rotatable drawing block, the die-holder, means whereby the die-holder moves away from its wire-drawing position when the tension of the wire is released, and the driving means for the drawing-block, of means for braking the rotation of the block, and operating connections between the die-holder on one hand, and the driving and braking means on the other, said connections being arranged to be operated by said movement of the die-holder to disconnect the driving means from the drawing block and to apply the braking means thereto. 110

2. In a wire-drawing machine, the combination with the rotatable drawing-block, the die-holder and means automatically operating to move the die-holder from its drawing position when the wire tension is released, of means for braking the rotation of the drawing-block, and operating connections between the die-holder and the 115 120 125

braking means, said connections being operated by said movement of the die-holder to operate the braking means.

3. In a wire-drawing machine, the combination with the die-holder, the rotatable drawing block and driving means therefor, of means for braking the rotation of the drawing-block, an operator's control, operating connections between said control and the driving means and braking means to disconnect the former and apply the latter and reversely; means for automatically moving the die-holder from its drawing position when the wire tension is released, and operating connections between the die-holder and operator's control whereby said movement of the die-holder causes the operator's control to operate the connections to the driving and braking means.
- 20 4. In a wire-drawing machine, the combination with the die-holder and the rotatable drawing block, of means for braking the rotation of the drawing block, an operator's control, operating connections between said control and the braking means; means for automatically moving the die-holder from its drawing position when the wire-tension is released, and operating connections between the die-holder and the operator's control whereby said movement of the die-holder causes the operator's control to operate the connections to the braking means.

5. In a wire-drawing machine, the combination with the rotatable drawing-block and separable driving means therefor, of means for braking the rotation of the drawing-block, said means being applied to the block, an operator's control, and operating connections between said control and the driving and braking means respectively, the connections between the control and braking means being provided with a lost motion device whereby the operator's control may be operated to release the brake without applying the power to the block.

6. In a wire-drawing machine, the combination with the rotatable drawing-block and driving means therefor, and the die-holder, of means for braking the rotation of the driving-block, operating connections to both the driving and braking means, a common operator's control for said respective connections whereby the one may be operated and the operation of the other be discon-

tinued at the will of the operator; and operating connections between said operator's control and the die-holder whereby the operation of the driving means is stopped and the brake applied independent of the will of the operator.

55 7. In a wire-drawing machine, the combination with the rotatable drawing-block, of a brake shoe conformed for braking engagement therewith, a compression spring arranged to force said shoe against said block, and operating connections to said shoe whereby it is alternatively forced against said spring away from said block and permitted to be forced by said spring against said block.

60 8. In a wire-drawing machine, the combination with the rotatable drawing-block, of a brake constructed and arranged to have its shoe applied to said block, a treadle lever extending below the drawing block and 75 brake and pivoted to the machine below the drawing-block and brake, an adjustable connection having its lower end pivoted to the treadle-lever, and operating connections between said adjustable connection and the 80 shoe of the brake.

85 9. In a wire-drawing machine, the combination with the rotatable drawing block, die-holder and means controlling the rotation of the drawing-block, of operating connections between the die holder and said controlling means, said means having a rigid member as a part thereof, and an adjustable weight upon said rigid member counterbalancing said die-holder and arranged in 90 said operating connections to cause the movements of the die-holder away from its drawing position when the wire tension is released.

10. In a wire-drawing machine, the combination with the die-holder pivotally mounted to be movable vertically, of a vertically movable member having a loose connection with the die-holder, a horizontal operating connection pivoted to the lower 100 end of said vertically movable member, and a weight mounted on said horizontal connection to counterbalance the die-holder.
